2,391,517

THREAD TAKE-UP FOR SEWING MACHINES

Charles F. Rubel, Chicago, Ill., assignor to Union Special Machine Company, Chicago, Ill., a corporation of Illinois

Application April 9, 1942, Serial No. 438,222

19 Claims. (Cl. 112—248)

This invention relates to devices for taking up and yielding the needle thread in a sewing machine at the appropriate times in each cycle to allow for proper stitch formation and to avoid excessive slack, likely to become entangled in the moving parts. It relates especially to the provision of such devices on a lock stitch sewing machine, in the operation of which a relatively large take-up action is required.

An object of the invention has been to provide a simple but effective take-up, for machines of the character mentioned, which involves continuously rotating parts, of relatively small radius, operating at a uniform angular speed. Vibrations incident to the high speed operation of reciprocating, or otherwise accelerating and decelerating devices are completely avoided. Moreover, the action of the devices is such that the take-up and yield of the thread is effected smoothly, without jerking or otherwise placing a heavy strain upon the thread, such as is likely to produce breakage at the high speeds now commonly encountered in commercial operations.

A feature of the invention is the provision of a pair of rotary take-up members, arranged for simple rotation at different angular speeds about a common axis. Thus, a very simple and compact construction is provided for carrying out the primary purpose of the invention. The arrangement is such, moreover, that the two rotary take-up means, operating in different planes, are adapted at times to combine their effect and at other times to produce a differential effect, in taking up and yielding the thread, so as to meet with precision the requirements of the stitch-forming devices.

A further feature of the invention is the provision of a pair of rotary take-up members acting upon the thread at opposite sides of a fixed thread guide, one of the members having a cam-like configuration, the periphery of the cam engaging the thread to provide just the required take-up action at all positions of the members. In the preferred construction the cam-like element is arranged to effect two take-up actions upon the thread during each stitch-forming cycle.

Other objects, features and advantages of the invention will appear from the detailed description of an illustrative form of the same which will now be given in conjunction with the accompanying drawings, in which:

Fig. I is a view partly in side elevation and partly in longitudinal, vertical section through a machine embodying the invention.

Fig. II is a view primarily in end elevation but

partly in vertical section along the line of stitching.

Figs. III, IV, V and VI are a series of views, largely in end elevation but partly in section along the line of stitching, disclosing the improved take-up means in relation to the rotary hook at different stages in a cycle of operation.

Fig. VII is a longitudinal, vertical section through the improved take-up means, the operating connections therefor, and associated devices.

Fig. VIII is a detail view in vertical section along the line VIII—VIII of Fig. VII, showing the driving connections for the take-up means.

Fig. IX is a vertical section along the line IX—IX of Fig. VII.

Fig. X is a vertical section along the line X—X of Fig. VII, and

Fig. XI is a top plan view of the take-up means and associated devices.

Referring now to the drawings, the invention has been illustrated in connection with a lock stitch sewing machine of the type more fully disclosed in the patent to Christensen and Rubel, No. 2,113,572, granted April 12, 1938. Reference may be had to said patent for a fuller description and showing of the stitch-forming and work-feeding devices and the operating means therefor. These will be but briefly described herein.

As illustrated, the machine may have a frame comprising a vertical standard 10 extending upwardly from one end of a base portion 11 and having at its upper end a laterally extending, overhanging arm 12. This arm carries, at its free end, a needle head 12a. A shaft 13, extending longitudinally of the overhanging arm, projects outwardly through the rear wall of the standard 10 and is provided with a combined pulley and hand wheel 14 through which power is supplied to the machine. Suitable gearing 15 serves to connect the shaft 13 with a parallel shaft 16 extending longitudinally of the base 11.

At the free end of the shaft 13 there is mounted a head 17 carrying a crank pin 18 connected, by a link 19, with a vertically reciprocable needle bar 20 having a needle 21 suitably secured to its lower end. Adjacent the needle bar is provided the usual presser bar 22 carrying at its lower end a presser foot 23, arranged to engage the work and urge it yieldingly against the work supporting surface of the base 11. Any suitable means, such as a lever 24, may be provided for lifting the presser bar against the action of a suitable spring (not shown). A thread guide 25, secured to the presser bar, is adapted to be lifted with the latter to accommodate different thicknesses of the

work and also to provide a certain amount of slack in the needle thread whenever the presser foot is raised.

Beneath the presser foot a feed dog 26 is provided, this being arranged to pass upwardly through suitable slots in a throat plate forming part of the work supporting surface. Appropriate connections are provided for imparting a four-motion operation to the feed dog to advance the work during the desired portion of each cycle of the machine. For this purpose the feed dog is carried by a feed bar 27 pivotally mounted on a rock member 28, the latter being adapted for oscillation by suitable connections (not shown) from the shaft 16. A downwardly extending arm 29 of the feed bar is connected with a link 30 whose upper end is mounted on and operated by a crank pin 31 at the end of the shaft 16. This provides for the desired up-and-down movements of the feed dog.

A rotary hook 32, secured to the end of a horizontally disposed shaft 33 within the base 11, is arranged to cooperate with the needle 21 in the formation of a lock stitch in well known manner. Shaft 33 is adapted to be rotated at twice the angular speed of the shaft 16 through a pinion 34 secured to the shaft 33 and a gear 35 secured to the shaft 16.

Adjacent the head 17 there is secured to the shaft 13 a pair of gears 36 and 37, these being joined together by a series of screws 36a (Fig. VII) to form a single unit. Gears 36 and 37 cooperate, respectively, with gears 38 and 39, which are of such size that the gear 38 will be given two revolutions for each revolution of the shaft 13 while the gear 39 will, at the same time be given only one revolution. Gear 38 is keyed to a sleeve 40 journaled within a bushing 41 carried by the needle head. Within the sleeve 40 there is journaled a shaft 42 to which is secured the gear 39. At the opposite end of the shaft 42 is secured an outer, rotary, take-up member 43 comprising an outer disc 43a, largely cut out to reduce its weight, and an inner disc 43b. There is similarly secured to the outer end of the sleeve 40 a second, or inner, rotary take-up member 44 comprising a pair of discs 44a and 44b. The two take-up members are spaced axially with respect to each other and are separated by a stationary plate 45 attached by screws 46 to the end face of the needle head. In view of the gearing hereinbefore described, take-up member 43 will be operated at the same frequency as the needle bar, i. e., one revolution for each reciprocation of the needle bar. The take-up member 44, on the other hand, will be given two revolutions for each one of the member 43 and hence will be operated at the same frequency as the rotary hook.

Referring now particularly to Fig. II, the needle thread 47, supplied from any suitable source (not shown), is first passed through a series of openings in a guide 48 secured to the end face of the needle head. From this it is passed around suitable thread tensioning means 49, thence over a spring-tensioned check wire 50 carried by an adjustable plate 50a (in the manner disclosed in the pending application of Christensen et al., Ser. No. 369,248, filed December 9, 1940), thence downwardly under the guide 25, then upwardly, behind a plate 51 secured at one end to the face of the needle head, up to the take-up member 44, around a cam-like plate 52 forming part of said take-up member between the two outer face discs 44a and 44b; thence outwardly beyond the periphery of the face discs,

under a pin 45a projecting rearwardly from the plate 45 and adapted to be inserted in any one of a series of holes 45b therein, then around a roller 53 forming part of a stationary or fixed guide secured to the plate 45 and disposed intermediate the plane of the plate 52 and the plane of the orbital path of a pair of pins or rollers 54, thence across a pin 53a at the inner end of the guide 53 to the take-up member 43, across the path of said pins or rollers 54 forming a part thereof extending between the outer face discs 43a and 43b, then downwardly to a stationary guide 55, thence through a guide 56 carried by the needle bar, then through the eye of the needle, and finally down through the work to form a loop beneath the work around a portion of the bobbin holder.

Assuming that the parts, at the commencement of a particular cycle, are in the positions indicated in Fig. II, it will be noted that the needle

is rising and is near the upper limit of its movement. The loop thrown out by the needle at the commencement of its upward movement has been engaged by the beak 32a of the rotary hook and has been extended by the hook to substantially its maximum size. It extends almost across the full diameter of the bobbin holder and has been passed over the bobbin thread 57. At this stage in the cycle it will be noted that the two thread take-up members have very nearly their minimum effect upon the path of the thread, i. e. the course of the thread from the guide 25 to the guide 55 is substantially its minimum length.

During the initial portion of the movement from the Fig. II position toward that of Fig. III, the cam-like element 52 of the member 44 will yield a slight additional amount of thread as the flat side 52a is carried counterclockwise and allows the course of the thread to straighten out between the guide 25 and the top of the element 52. At the same time the curved portion 52b of the cam-like element begins to take up a slight portion of the thread yielded by the flat side 52a but the net result is to supply enough extra thread to complete the loop around the bobbin holder. During this initial movement from the Fig. II position, the rollers 54 of the outer take-up member 43 make little or no change in the course of the thread between the pin 53a and the guide 55.

Now, however, as the parts shift further toward the Fig. III position, the rotary hook will have passed its maximum requirement of thread and will have begun to rapidly yield the loop from around the bobbin holder. The thread so yielded is taken up by both of the members 43 and 44 due to the action of the rollers 54 and the curved portion 52b of the cam-like element 52. This take-up action continues on the part of both of the members into the Fig. IV position, in which the maximum radius portion 52c of the cam-like element is effective and in which the forward roller 54 of the outer take-up member is continuing to form a more extended loop between the stationary guides 53 and 55. At this point in the operation, the needle is at substantially the upper limit of its travel and the loop previously thrown about the bobbin holder is almost completely taken up. In proceeding to the Fig. V position the rollers 54 of the outer take-up member, continue to their take-up action at a substantial rate but at the same time the cam-like element 52 will be yielding a portion of the thread demanded by the rollers 54. The differential action between the two take-up members is just

sufficient to draw up the remaining portion of the loop previously around the bobbin holder and to draw this loop relatively slowly but tightly against the under side of the work. In the course of this action, the check wire 50 is drawn downwardly, against the action of its spring, to substantially the level of the under surface of the thread engaging portion of guide 25 and in so doing yields the last amount of thread required by the outer take-up member. This maximum take-up action occurs slightly before the Fig. V position is reached, just about as the forward roller 54 reaches, or is carried slightly beyond, the vertical plane through the axis of member 43. In passing from the Fig. IV to the Fig. V position, the needle will descend, sliding its eye along the thread until the point of the needle is but a small distance above the work. At the same time the rotary hook will have commenced its idle rotation and the thread-engaging beak 32a will have traveled about 90° from its uppermost position.

In passing now from the Fig. V to the Fig. VI position, the needle continues to descend, reaches its lowermost position, and commences its upward movement. The thread-engaging beak 32a of the rotary hook has completed its idle rotation and is about to seize, or has just seized, the new loop cast by the needle at the commencement of its upward movement. During this period, between the Fig. V and the Fig. VI position, the rollers 54 will have yielded the thread at a relatively rapid rate by a substantial shortening of the course between the fixed guides 53 and 55. It will be noted incidentally, that this course, during the period in question, carries the thread around a portion of the fixed guide 25. Some of the yielded thread will have been taken up by the needle which will have carried the loop downwardly through the work into the path of the rotary hook. However, a substantial portion of the thread yielded by the rollers 54 will have been taken up by the inner cam-like take-up element 52. This element, operating at twice the angular speed of the outer take-up member, will have attained substantially its maximum take-up action by the time the Fig. VI position is reached.

Now, in proceeding from the Fig. VI position back to the Fig. II position, both of the take-up members will yield the thread at a relatively rapid rate and their combined action at this time is sufficient to provide the thread for the formation of the loop around the bobbin holder to the extent required in arriving at the Fig. II position.

In a preferred construction of the new take-up the maximum radial distance from the axis of the shaft 42 to the outermost portions of the cam 52 and of the rollers 54 is not more than 1.5 inches, thus avoiding excessive centrifugal forces. The combined action of the two take-up means, when held within this dimension, is adequate for the purposes of the usual rotary hook.

While an illustrative form of the invention has been described in considerable detail, it will be understood that various changes may be made in the construction, arrangement and inter-relation of the several parts without departing from the general principles and scope of the invention. The terms and expressions used herein have been used as terms of description and not of limitation.

What I claim is:

1. In a sewing machine a reciprocating needle bar, a needle carried thereby, complementary

stitch forming means cooperating with said needle and acting upon a thread carried thereby, and take-up means cooperating with said thread in timed relation with said needle bar and complementary stitch forming means, said take-up means comprising a plurality of coaxial, rotary members, each mounted for simple rotation, and means for operating said members at different angular speeds.

10 2. In a sewing machine a reciprocating needle bar, a needle carried thereby, complementary stitch forming means cooperating with said needle and acting upon a thread carried thereby, and take-up means cooperating with said thread in timed relation with said needle bar and complementary stitch forming means, said take-up means comprising a plurality of coaxial, rotary members, said members acting upon said thread in different vertical planes, and means for operating said members at different angular speeds.

15 3. In a sewing machine a reciprocating needle bar, a needle carried thereby, complementary stitch forming means cooperating with said needle and acting upon a thread carried thereby, and take-up means cooperating with said thread in timed relation with said needle bar and complementary stitch forming means, said take-up means comprising a plurality of coaxial, rotary members, each mounted for simple rotation, and means for operating said members at uniform but different angular speeds.

20 4. In a sewing machine a reciprocating needle bar, a needle carried thereby, complementary stitch forming means cooperating with said needle and acting upon a thread carried thereby, and take-up means cooperating with said thread in timed relation with said needle bar and complementary stitch forming means, said take-up means comprising a plurality of coaxial, rotary members arranged to move in spaced vertical planes, fixed position thread guiding means intermediate the planes of movement of said rotary members, and means for operating said members at different angular speeds.

25 5. In a sewing machine a reciprocating needle bar, a needle carried thereby, complementary stitch forming means cooperating with said needle and acting upon a thread carried thereby, operating means for driving said needle bar and said stitch forming means, a fixed thread guide, a pair of coaxial, rotary take-up members arranged respectively to cooperate with said thread in advance of and after its engagement with said guide, and connections from said operating means 30 for rotating said members at different angular speeds.

35 6. In a sewing machine a reciprocating needle bar, a needle carried thereby, complementary stitch forming means cooperating with said needle and acting upon a thread carried thereby, operating means for driving said needle bar and said stitch forming means at different frequencies, a fixed thread guide, a pair of coaxial, rotary take-up members arranged respectively to 40 cooperate with said thread in advance of and after its engagement with said guide, and connections from said operating means for rotating one of said members at the frequency of said needle bar and the other of said members at the frequency of said complementary stitch forming means.

45 7. In a sewing machine a reciprocating needle bar, a needle carried thereby, complementary stitch forming means cooperating with said needle and acting upon a thread carried thereby, operating means for driving said needle bar and

70 75

said stitch forming means, a fixed position thread guide, a pair of coaxial, rotary take-up members arranged respectively to cooperate with said thread in advance of and after its engagement with said guide, and connections from said operating means for rotating said members at different angular speeds, the outermost thread engaging portions of said members being at a distance of not more than 1.5 inches from the axis of rotation of said members.

8. In a sewing machine a reciprocating needle bar, a needle carried thereby, complementary stitch forming means cooperating with said needle and acting upon a thread carried thereby, operating means for driving said needle bar and said stitch forming means, a fixed thread guide, a pair of coaxial, rotary take-up members arranged respectively to cooperate with said thread in advance of and after its engagement with said guide, and connections from said operating means for rotating said members at different angular speeds, said members and connections being so constructed and arranged that the thread engaging portions of said members at times produce an additive effect and at other times a differential effect upon said thread.

9. In a lockstitch sewing machine a main drive shaft, a reciprocable needle operated by connections from said shaft, a rotary hook arranged to cooperate with said needle in stitch formation, connections from said shaft for rotating said hook at a speed of two revolutions for each reciprocation of said needle, and a pair of coaxial rotary take-up members driven by said shaft and arranged to cooperate with a thread carried by said needle, one of said members being rotated at the same speed as said rotary hook and the other member being rotated at half said speed.

10. In a lockstitch sewing machine a main drive shaft, a reciprocable needle operated by connections from said shaft, a rotary hook arranged to cooperate with said needle in stitch formation, connections from said shaft for rotating said hook at a speed of two revolutions for each reciprocation of said needle, and a pair of coaxial rotary take-up members driven by said shaft and arranged to cooperate with a thread carried by said needle, one of said members having means only adjacent its periphery for engaging said thread and the other of said members having thread engaging surfaces adjacent its axis and adjacent its periphery, said members being rotated at uniform but different speeds.

11. In a lockstitch sewing machine a main drive shaft, a reciprocable needle operated by connections from said shaft, a rotary hook arranged to cooperate with said needle in stitch formation, connections from said shaft for rotating said hook at a speed of two revolutions for each reciprocation of said needle, and a pair of coaxial rotary take-up members driven by said shaft and arranged to cooperate with a thread carried by said needle, one of said members having thread engaging surfaces only adjacent its periphery and the other of said members having thread engaging surfaces at widely different distances from the axis thereof, said members being rotated at different but uniform speeds.

12. In a lockstitch sewing machine a main drive shaft, a reciprocable needle operated by connection from said shaft, a rotary hook arranged to cooperate with said needle in stitch formation, connections from said shaft for re-

tating said hook at a speed of two revolutions for each reciprocation of said needle, and a pair of coaxial rotary take-up members driven by said shaft and arranged to cooperate with a thread carried by said needle, one of said members having thread engaging surfaces only adjacent its periphery and the other of said members having a cam-like thread engaging element of substantial area, said last mentioned member being rotated at twice the speed of said one of said members.

13. A thread take-up for a sewing machine which comprises a pair of rotary members, one of said members having its thread engaging surfaces at a substantially uniform radial distance from the axis of rotation of said member, the other of said members having an unbroken thread engaging surface of substantially continuously varying radius from the axis of rotation of said member, means for rotating said members at different angular speeds, and thread guiding means constructed and arranged to guide a thread into the paths of said members in directions normal to the axes thereof for constant manipulation of the thread by said members.

14. A thread take-up for a sewing machine which comprises a pair of coaxially arranged, rotary members, one of said members having its thread engaging surfaces at substantially the same radial distance from the axis of rotation of said member, the other of said members having thread engaging surfaces at continuously varying radial distances from the axis of rotation thereof, and means for rotating said members at different angular speeds.

15. A thread take-up for a sewing machine which comprises a pair of coaxially arranged rotary members, one of said members having its thread engaging surfaces at substantially the same radial distance from the axis of rotation of said member, the other of said members having a cam-like thread engaging element so shaped and arranged that substantially all portions of its periphery will engage the thread during rotation of said member, means for rotating said members at uniform angular speeds, and thread guiding means constructed and arranged to guide a thread into the paths of said members for constant manipulation thereof by said members.

16. A thread take-up for a sewing machine which comprises a pair of rotary members, one of said members having its thread engaging surfaces at substantially the same radial distance from the axis of rotation of said member, the other of said members having a cam-like thread engaging element so shaped and arranged that substantially all portions of its periphery will engage the thread during rotation of said member, connections for rotating said other of said members at a multiple of the angular speed of said one of said members, and thread guiding means constructed and arranged to guide a thread into the paths of said members for constant manipulation thereof by said members, said guiding means including a roller for engaging said thread between its points of engagement by said pair of members.

17. A thread take-up for a sewing machine which comprises a plurality of coaxially arranged rotary take-up members, one of said members having thread engaging means at a predetermined radial distance from the axis of rotation of said member, the other of said members having a cam-like thread engaging element arranged to hold portions of the thread at

continuously varying distances from the axis of rotation thereof, and means for rotating said members at uniform angular speeds.

18. A thread take-up for a sewing machine which comprises a pair of coaxially arranged rotary members, one of said members having its thread engaging surfaces at substantially the same radial distance from the axis of rotation of said member, the other of said members having a cam-like thread engaging element so shaped and arranged that substantially all portions of its periphery will engage the thread during rotation of said member, means for rotating said members at uniform angular speeds, and thread guiding means constructed and arranged to guide a thread into the paths of said members for constant manipulation thereof by

said members, said cam-like element being adapted to impart two take-up actions for each take-up action of said one of said members.

19. In a sewing machine a needle thread take-up comprising a rotatable cam-shaped take-up member of continuously varying radius from the axis of rotation of said member, a second take-up member adjacent one side of said first-named member and arranged to move in a circular orbit concentric with the axis of rotation of said first-named member, means for operating said take-up members, and thread guiding means for guiding a thread into successive engagement with said members for constant and concurrent manipulation by both of said members.

CHARLES F. RUBEL.
